UNITED STATES PATENT OFFICE.

LEON LUKACHER, OF DETROIT, MICHIGAN.

GAME-TABLE.

1,225,260.

Specification of Letters Patent.

Patented May 8, 1917.

Application filed December 14, 1914, Serial No. 377,152. Renewed January 10, 1917. Serial No. 141,694.

To all whom it may concern:

Be it known that I, LEON LUKACHER, a citizen of the United States, residing at Detroit, in the county of Wayne and State of Michigan, have invented certain new and useful Improvements in Game-Tables, of which the following is a specification.

This invention relates to game tables of the bagatelle type, and its object is to provide a table of this kind embodying certain novel features whereby the game is made more interesting.

The invention also has for its object to provide a novel and improved pin-setting mechanism.

These objects are attained by means of a combination and arrangement of parts to be hereinafter described and claimed, reference being had to the accompanying drawing in which—

Figure 1 is a plan view of the table; Fig. 2 is a cross-section on the line 2—2 of Fig. 1; Fig. 3 is a longitudinal section on the line 3—3 of Fig. 1; and Fig. 4 is a sectional view showing the pin-setting mechanism.

Referring specifically to the drawing, 5 denotes the table top, the same being suitably supported on legs 6. The table top is inclined upward toward the head-end, and 10 said end is rounded as shown in Fig. 1. On each side of the table is an alley which leads from the foot of the table to the head-end thereof. These alleys are formed by an upstanding marginal wall 7 extending along 15 the sides of the table and around the curved head-end thereof, and two upstanding walls or partitions 8 extending lengthwise of the table top on opposite sides of the longitudinal center line thereof. The walls 8 extend 20 parallel to the wall 7 in spaced relation therewith, and terminate a short distance from the head-end of the table top so that the alleys open to this portion of the table 25 top. At the foot of the table top the alleys are closed by transverse walls 9.

On each side of the center line of the table top 5, the latter has a channel 10. These channels start at the upper end of the walls 8 and extend along the inner side thereof, 30 and at the foot of the table top the channels are joined by a cross-channel 11. At the middle of the channel 11, the table top has an opening 12 beneath which latter is mounted a basket or other suitable ball receptacle 13, placed so that it is accessible to the players.

At the head-end of the table top 5 is a slight depression 14 which is for a purpose to be presently described, said depression being at the center line of the table top. 60

At the foot of the table top, between the channels 10 and ahead of the cross-channel 11, is a field in which are set pins 15 which latter are designed to be knocked down when playing the game. 65

The game is played by rolling a ball up either one of the alleys at the sides of the table top, the alley at the right being used by right-handed players, and the alley at the left by left-handed players. The pins 15 being set, the player, standing at the foot of the table, rolls a ball up the alley. The player's ball, upon encountering the curved wall 7 at the head-end of the table, either rolls down the table top between the channels 10, or it returns to the foot of the table by the other alley. If it rolls down between the channels it is liable to enter one of the channels before it reaches the pins 15, but if it keeps at the middle of the table it 70 strikes the pins 15, knocking down the same. 75

If the player's ball should fall into the depression 14, it will rest there an instant and then roll down the center of the table, striking the group of pins 15 centrally so 80 that all or most of them are knocked down. The pins 15 are arranged in a triangle with the apex at the center of the table top and facing the head-end thereof. If the player's ball rolls into one of the channels 10 it is 85 forfeited. It will thus be seen that the player, in order to knock down the largest number of pins, must roll the ball so that it will come down the center of the table top and as this requires some degree of skill 90 the game is made interesting. The forfeited balls roll along the cross-channel 11 and drop through the opening 12 into the receptacle 13. 95

The pin field, or that portion of the table 100 top 5 on which the pins 15 are set, is level so that the pins may remain upright until knocked down.

The following mechanism is provided for setting the pins 15, the same being illustrated in Fig. 4. 105

As shown, the table top 5 is provided with openings 16 at the points where the pins are set, these openings extending entirely through the table. To the base of 110 each pin is connected a flexible cable or line 17 which extends through the opening over

which the pin seats. Beneath the table top is hinged, as indicated at 18, a cup-shaped receptacle 19 in which is held a weight 20 to which the lines 17 are attached. To the 5 receptacle is connected an operating line 21 which passes over a guide pulley 22 mounted on the under side of the table top and is connected to a hand lever 23 provided with a suitable locking device 24, which latter 10 may be in the form of a toothed segment as shown. When the pins are standing erect, the weight 20 rests in the receptacle 19, the lines 17 being slack so that the pins may be knocked down when struck by the ball. 15 To set the pins, the receptacle 19 is dropped slightly by operating the hand lever 23, whereupon the weight 20 drops and pulls the lines 17 taut, and thereby sets the pins upright again. After the pins have been 20 set, the receptacle is elevated to raise the weight and thus slacken the lines 17.

I claim:

1. A game table comprising a top which is inclined toward its head-end and has 25 alleys along its opposite longitudinal edges, said table top also having channels extending along the alleys on the inside thereof and a cross-channel connecting said channels at the foot of the table top, said cross- 30 channel having an outlet, and a curved wall extending between the alleys near the head-end of the table top.

Copies of this patent may be obtained for five cents each, by addressing the "Commissioner of Patents, Washington, D. C."

2. A game table comprising a top which is inclined toward its head-end and has alleys along its opposite longitudinal edges, 35 said table top also having channels extending along the alleys on the inside thereof and a cross-channel connecting said channels at the foot of the table top, said cross-channel having an outlet, a curved wall extending between the alleys near the head-end of the table top, and a pin field at the foot-end of the table.

3. A game table comprising a top which is inclined toward its head-end and has alleys along its opposite longitudinal edges, 40 said table top also having channels extending along the alleys on the inside thereof and a cross-channel connecting said channels at the foot of the table top, said cross-channel having an outlet, a curved wall extending between the alleys near the head-end of the table top, and a pin field at the foot-end of the table, the head-end of the table having a depression which is in longitudinal alinement with the center of the pin field.

In testimony whereof I affix my signature in presence of two witnesses.

LEON LUKACHER.
